CARBURETER.

1,210,799.

Specification of Letters Patent.

Patented Jan. 2, 1917.

Application filed March 3, 1916. Serial No. 81,865.

To all whom it may concern:

Be it known that we, JOHN J. HAWXHURST, Jr., and EDWARD F. NICOLAI, residents, respectively, of Brooklyn, in the county of Kings and State of New York, and Port Washington, in the county of Queens and State of New York, both citizens of the United States, have invented certain new and useful Improvements in Carbureters for Internal Combustion Engines, of which the following is a specification.

Our invention relates to carbureters designed to be used with internal combustion engines to produce a combustible mixture from air and a suitable liquid fuel by atomizing the fuel, and mixing air therewith; and more particularly to that type or class of carbureters designed for use with the power systems of automobiles and similar self-propelled vehicles and in which a preliminary mixture containing a comparatively large portion of liquid fuel is first formed by the atomizing action of a current of air caused to flow past a fuel supply nozzle by the suction or vacuum producing action of the engine, which preliminary mixture is subsequently diluted to produce a proper combustible mixture by a further supply of air admitted through ports and passages controlled by an automatically operating air valve, the operation of which is likewise dependent upon the suction or vacuum producing action of the engine with which the carbureter is used. In such carbureters the elements which produce the rich preliminary mixture in the normal operation of the engine, that is when the engine is operating under normal load conditions, and at high speed, serve to produce a combustible mixture suitable for supplying the engine when it is running slowly and without load, or idling, and when the engine is started; while the automatic diluting valve referred to comes into operation as the speed of the engine increases and admits an additional quantity of air to thereby dilute the rich mixture and form a proper combustible mixture for use when the engine has attained its normal speed, and is operating under normal load conditions.

The objects of our invention are to pro-

vide a carbureter of the type above referred to in which a better and a more economical production of the combustible mixture necessary to supply the engine when it is running without load, or idling, is secured; to provide a carbureter in which an improved form and arrangement of ports, passages and air valve whereby the supply of auxiliary air to dilute the rich mixture produced when the engine is operating at normal speed, and under normal load conditions, is provided; to provide a carbureter in which the operation of the auxiliary air valve may be regulated and controlled, and the movements of said valve cushioned, whereby a smoother and a more uniform action of said valve is secured; to provide a carbureter in which the various parts may be more readily adjusted relative to one another, and the carbureter thus more easily and better adapted to the engine with which it is to be used, than has heretofore usually been the case; to provide a carbureter which is simple in construction and effective for the purpose for which it is designed, and one in which the combustible mixture will be more nearly uniform throughout the entire range of speed and load conditions of the engine with which it is to be used than has been the case in prior carbureters of the type to which our invention relates; and to otherwise improve upon and enhance the efficiency of carbureters designed for use with internal combustion engines.

With the above and other objects of invention in view, our invention consists in the improved carbureter for internal combustion engines illustrated in the accompanying drawing, described in the following specification, and particularly claimed, and in such variations and modifications thereof as will be obvious to those skilled in the art to which our invention relates.

In the drawing accompanying and forming a part of this application and wherein the preferred embodiment of our invention is illustrated, and wherein the same reference numerals are employed to designate like parts in the several figures: Figure 1 is a view showing a section of our improved carbureter taken upon a vertical central plane indicated by the line 1—1, Fig. 2; and Fig. 2 is a view showing a section thereof

upon transverse planes indicated by the broken line 2—2, Fig. 1.

Referring to the drawing, the reference numeral 3 designates the main or body portion and 4 the base portion or bottom of a two-part exterior casing within which a carbureting and mixing chamber 5 is provided, said body and base portions being formed separate from one another and secured together by a threaded connection at the lower end of the body portion in the preferred embodiment of our invention illustrated.

Depending from the bottom or base member 4 is a tubular portion 6 within which a vertically arranged air passage 7 is formed, said passage being preferably contracted at its middle portion to form a Venturi, as shown; the lower end of said air passage being in open communication with the atmosphere through a spider 8 in threaded engagement with the lower end of the tubular portion, and an adjustable connection 9; which connection is provided in order that the carbureter may be connected with a source of heated air, if desired. The upper end of the air passage 7 extends through an annular projection 10 formed upon the lower casing member 4 and extending up into the interior of the casing, as shown, and terminates in an upwardly extending annular flange 11.

The reference numeral 12 designates a float chamber surrounding the depending tubular portion 6 and held in place between the spider 8 and the under side of the base member 4, and to which chamber a liquid fuel is supplied through a fuel supply pipe to be connected with the nipple 13, the level of fuel in the float chamber being controlled and kept constant by means of a float 14 acting upon a fuel supply valve 15 through a bifurcated lever 16 pivotally supported at 17, as is usual in carbureters of the type to which our invention relates.

Located within the air passage 7 is a fuel supply nozzle 18 which is placed in communication with the interior of the float chamber through a fuel supply passage 19 as shown; and the carbureter casing is provided with an outlet passage 20 through which the combustible mixture flows to the engine with which the carbureter is used, the flow through said passage being ordinarily controlled by means of a valve 21 carried by an oscillating shaft 22, as is usual in carbureters.

Surrounding the upper end of the air passage 7 and located within the carbureter casing is a vertically adjustable annular valve seat 23, the same being preferably adjustable upon the annular projection 10 as by being in threaded engagement therewith, as shown; the adjustment of said valve seat being provided for by providing a project-

ing annular flange 24 at the lower end of said valve seat, and a series of recesses 26 at the periphery of said flange, in the embodiment of our invention illustrated. Access to said flange and recesses may be had through one or more of the auxiliary air inlet ports 27 provided in the carbureter casing for the admission of additional air to dilute the rich mixture first formed; and said valve seat may be rotated to adjust its position, vertically, by means of a suitable tool passed through an air port and inserted into the recesses. It will be understood, however, that other means may be provided for adjusting the valve seat, as our invention includes an adjustable valve seat in combination with other elements, together with means for adjusting said valve seat, as particularly claimed hereinafter. A spring pressed plunger 28 is carried by the adjustable valve seat in the form of our invention illustrated, the lower end of which plunger enters one of a series of depressions 29 provided in the base portion 4 to thereby hold said seat in position and prevent accidental rotation of the seat after it has been adjusted into proper position.

The interior of the carbureter casing is formed with or shaped to provide annular concentric portions 30, 31 of different diameters, and 32 designates a vertically movable annular air valve located within the carbureter casing and having concentric annular portions 33, 34 which move in contact with the concentric portions aforesaid of the interior of the casing, whereby an air chamber 35 is provided between the air valve and the carbureter casing. The lower end of the said air valve is provided with an annular portion 25 which co-operates with the adjustable valve seat 23 and contacts therewith when said air valve is in its lowermost position; and the lower end of said valve is provided with a depending annular portion or rim 36 which lies opposite and obstructs the flow of air through the auxiliary air inlet ports 27 when said valve is in its lowermost position, as shown.

The air valve 32 is operatively connected with a metering or needle valve 37, the lower end of which enters into and controls the flow of fuel through the fuel supply nozzle 18, the upper end of said needle valve being connected with a cross-bar 38 carried by the air valve as shown; and 39 designates an air passage extending from the interior of the carbureter casing through the wall of the air valve and into the air chamber 35.

The air chamber 35 is placed in communication with the external atmosphere through an air inlet passage 40 provided in a valve casing 41 in the embodiment of our invention illustrated; and 42 designates an inwardly opening check valve located in said air inlet passage and acting to permit air

to flow into said air chamber from the external atmosphere, and to prevent the flow of air from said chamber. The area of the air passage 40 may be regulated and adjusted by means of a valve 43 in threaded engagement with the valve casing 41, and said regulating valve is held in position after the parts have been properly adjusted by means of a lock nut 44.

- 10 When the engine with which our improved carbureter is used is running without load, or idling, as when the engine is permitted to run at reduced speed while the automobile is standing still, and also when the engine is started or is operating at low speed, the auxiliary air valve 32 is in its lowermost position with its annular portion 25 resting upon the adjustable valve seat 23 and all the air necessary to form the combustible mixture then enters the carbureter casing through the air passage 7 and atomizes the liquid fuel supplied through the fuel supply nozzle 18.

It is important that the air and fuel shall be so proportioned as to secure a smooth and uniform operation of the engine without misfires when the same is operating under the conditions above referred to, and likewise important that the consumption of fuel at such times shall be as low as possible, which results or ends are secured by the vertically adjustable valve seat 23; it being obvious that upward movement imparted to said valve seat will be transmitted through the air valve 32 to the fuel controlling valve 37, thus moving said valve out of the fuel supply nozzle 18 and permitting a more copious supply of fuel to the stream of air flowing past said nozzle; while downward movement of said adjustable seat will be accompanied by a decrease in the amount of fuel flowing through the fuel nozzle. Our improved carbureter can, therefore, by properly positioning the adjustable valve seat in question, be so adjusted as to secure a proper operation of the engine with which it is used when the same is running without load or at low speed, and so adjusted as to secure such operation with a minimum consumption of fuel.

As the speed of the engine increases the resulting suction or vacuum producing action reduces the pressure within the air chamber 35, the air flowing from said chamber through the passage 39 in the air valve 32, whereupon the pressure of the atmosphere acting upwardly upon said air valve causes it to move upward, thus moving the seating portion 25 of said valve off from the adjustable valve seat 23 and uncovering or opening the auxiliary air inlet ports 27. Additional air will thus be admitted to the carbureter casing through said ports and between the seats 23, 25 to mix with and dilute the rich preliminary mixture formed with-

in the air passage 7 when the engine is operating under normal speed and load conditions.

The air inlet ports 27 are obviously opened gradually as the air valve rises, because of the fact that the depending portion or rim 36 uncovers said ports progressively and does not open them entirely until the air valve reaches its uppermost position; and the extent of upward movement of said air valve is obviously dependent upon the vacuum produced within the air chamber 35.

The rapidity of the upward movement of the auxiliary air valve 32 is regulated, and the carbureter adjusted so as to secure an approximately uniform combustible mixture at engine speeds varying throughout a wide range, by means of the adjustable valve 43 which controls the flow of air through the air inlet passage 40; it being obvious that if air is permitted to flow into the air chamber 35 nearly as fast as it is withdrawn therefrom through the air passage 39 the valve will rise slowly, while if the flow through the passage 40 is more restricted said valve will rise more rapidly. Finally the inwardly opening check valve 42 in the air passage 40 closes upon a sudden or excessive upward movement of the air valve, due, for example, to a sudden opening of the throttle valve which controls the flow to the engine; whereupon the air chamber 35 will act as a dash pot and cushion the upward movement of said valve. Said check valve will not, however, interfere with the downward movement of the air valve; and said valve moves down and into contact with the adjustable valve seat 23, and into a position such that its depending rim 36 overlies and obstructs the auxiliary air inlet ports 27, when the engine stops or its speed is reduced materially below the speed at which it normally operates.

Having thus described and explained our invention, we claim and desire to secure by Letters Patent:

1. In a carbureter of the class described, a suitable casing having a vertically arranged air passage in communication with the atmosphere at its lower end, a series of auxiliary air inlet ports independent of said air passage and which ports are in direct communication with the atmosphere, and an outlet passage through which combustible mixture may flow; a fuel supply nozzle located within said air passage; an annular valve seat surrounding the upper end of said air passage; a vertically movable annular air valve located within said casing and having an annular seating portion adapted to cooperate with the valve seat at the upper end of said air passage, the lower end of said valve lying opposite the ports aforesaid when said valve is in its lowermost position and the periphery thereof moving in con-

- 4 tact with the interior of said casing; and a fuel supply valve carried by said air valve and adapted to control the flow of fuel through said fuel supply nozzle.
- 5 2. In a carbureter of the class described, a suitable casing having a vertically arranged air passage in communication with the atmosphere at its lower end, a series of auxiliary air inlet ports in communication with the atmosphere, and an outlet passage through which combustible mixture may flow; a fuel supply nozzle located within said air passage; a vertically adjustable annular valve seat surrounding the upper end 10 of said air passage; means for adjusting said valve seat; a vertically movable annular air valve located within said casing and having an annular portion adapted to coöperate with the valve seat at the upper end 15 of said air passage, the lower end of said valve lying opposite the ports aforesaid when said valve is in its lowermost position; and a fuel supply valve carried by said air valve and adapted to control the flow of fuel through said fuel supply nozzle.
- 10 3. In a carbureter of the class described, a suitable casing having a vertically arranged air passage in communication with the atmosphere at its lower end, a series of laterally disposed auxiliary air inlet ports located adjacent the upper end of said air 15 passage and also in communication with the atmosphere, and an outlet passage through which combustible mixture may flow; a fuel supply nozzle located within said air passage; an annular valve seat surrounding the upper end 20 of said air passage; a vertically movable annular air valve located within said casing and adjacent the upper end of said air passage, said air valve having a portion adapted to coöperate with the valve 25 seat at the upper end of said air passage, and a depending portion adapted to obstruct the flow of air through the ports aforesaid when said valve is in its lowermost position; and a fuel supply valve carried by said air valve and adapted to control the flow of fuel through said fuel supply nozzle.
- 20 4. In a carbureter of the class described, a suitable casing having a vertically arranged air passage in communication with the atmosphere at its lower end, laterally disposed ports located adjacent the upper end of said air passage and also in communication with the atmosphere, and an outlet 25 passage through which combustible mixture may flow; a fuel supply nozzle located within said air passage; an annular valve seat surrounding the upper end of said air passage; a vertically movable annular air 30 valve located within said casing and adjacent the upper end of said air passage and having an annular seating portion adapted to coöperate with the valve seat at the upper end of said air passage, and the lower 35 end of which valve lies opposite the ports aforesaid when said valve is in its lowermost position; and a fuel supply valve carried by said air valve and adapted to control the flow of fuel through said fuel supply nozzle.
- 30 5. In a carbureter of the class described, a suitable casing having a vertically arranged air passage in communication with the atmosphere at its lower end, a series of auxiliary air inlet ports located adjacent the upper end of said air passage and also in communication with the atmosphere, and an outlet passage through which combustible mixture may flow; a fuel supply nozzle located within said air passage; a vertically adjustable annular valve seat surrounding the upper end of said air passage; means for adjusting said valve seat; a vertically movable annular air valve located within said casing and adjacent the upper end of said air passage; and a fuel supply valve carried by said air valve and adapted to control the flow of fuel through said fuel supply nozzle.
- 35 6. In a carbureter of the class described, a suitable casing having a vertically arranged air passage in communication with the atmosphere at its lower end, a series of laterally disposed auxiliary air inlet ports in communication with the atmosphere, and an outlet passage through which combustible mixture may flow; a fuel supply nozzle located within said air passage; an annular valve seat surrounding the upper end of said air passage; a vertically movable annular air valve located within and the periphery of which moves in contact with the interior of said casing; said air valve having a seating portion adapted to coöperate with the valve seat at the upper end of said air passage and a depending portion adapted to obstruct the flow of air through the ports aforesaid when said valve is in its lowermost position; and a fuel supply valve carried by said air valve and adapted to control the flow of fuel through said fuel supply nozzle.
- 40 7. In a carbureter of the class described, a suitable casing having a vertically arranged air passage in communication with the atmosphere at its lower end, a series of auxiliary air inlet ports in communication with the atmosphere, and an outlet passage through which combustible mixture may flow; a fuel supply nozzle located within said air passage; a vertically adjustable annular valve seat surrounding and located adjacent the upper end of said air passage; means for adjusting said valve seat; a vertically movable annular air valve located within said casing and adjacent the upper end of said air passage; and an annular projection located within said casing and surrounding the upper end of said air passage.

5 nular valve seat carried by said projection and adjustable thereupon; a vertically movable annular air valve located within said casing and the lower end of which valve lies
10 opposite the ports aforesaid when said valve is in its lowermost position, said valve having an annular portion adapted to coöperate with the valve seat at the upper end of said air passage; and a fuel supply valve
15 carried by said air valve and adapted to control the flow of fuel through said fuel supply nozzle.

18. In a carbureter of the class described, a suitable casing having a vertically arranged air passage in communication with the atmosphere at its lower end, a series of auxiliary air inlet ports in communication with the atmosphere, and an outlet passage through which combustible mixture may 15 flow; a fuel supply nozzle located within said air passage; an annular projection located within said casing and surrounding the upper end of said air passage; an annular valve seat carried by said projection 20 and adjustable thereupon; a vertically movable annular air valve located within said casing and the lower end of which valve lies opposite the ports aforesaid when said valve is in its lowermost position, said valve 25 having an annular portion adapted to cooperate with the valve seat at the upper end of said air passage, and the periphery of said valve moving in contact with the interior of said casing; and a fuel supply valve 30 carried by said air valve and adapted to control the flow of fuel through said fuel supply nozzle,

9. In a carbureter of the class described, a suitable casing having a vertically arranged air passage in communication with the atmosphere at its lower end, a series of auxiliary air inlet ports in communication with the atmosphere, and an outlet passage through which combustible mixture may flow; a fuel supply nozzle located within said air passage; an annular projection located within said casing and surrounding the upper end of said air passage; an annular valve seat in threaded engagement with said projection; a vertically movable annular air valve located within said casing and the lower end of which valve lies opposite the ports aforesaid when said valve is in its lowest position, said valve having an annular portion adapted to coöperate with the valve seat at the upper end of said air passage; and a fuel supply valve carried by said air valve and adapted to control the flow of fuel through said fuel supply nozzle.

60. 10. In a carbureter of the class described, a suitable casing having a vertically arranged air passage in communication with the atmosphere at its lower end, a series of auxiliary air inlet ports in communication with the atmosphere, and an outlet passage

through which combustible mixture may flow; a fuel supply nozzle located within said air passage; air annular projection located within said casing and surrounding the upper end of said air passage; an annular valve seat in threaded engagement with said projection; a vertically movable annular air valve located within said casing and the lower end of which valve lies opposite

the lower end of which valve lies opposite the ports aforesaid when said valve is in its lowermost position, said valve having an annular portion adapted to cooperate with the valve seat at the upper end of said air passage, and the periphery of said valve moving in contact with the interior of said casting; and a fuel supply valve carried by said air valve and adapted to control the flow of fuel through said fuel supply nozzle. 75 80

11. In a carburetter of the class described, a suitable casing having a vertically arranged air passage in communication with the atmosphere at its lower end, a series of auxiliary air inlet ports in communication with the atmosphere, and an outlet passage through which combustible mixture may flow; a fuel supply nozzle located within said air passage; an annular projection located within said casing and surrounding the upper end of said air passage; an annular valve seat in threaded engagement with said projection; a vertically movable annular air valve located within said casing and the lower end of which valve lies opposite the ports aforesaid when said valve is in its lowermost position, said valve having an annular portion adapted to cooperate with the valve seat at the upper end of said air passage; the inner surface of said casing having concentric portions of different diameters, and the periphery of said air valve having also concentric portions of different diameters adapted to move in contact with the concentric portions of said casing, whereby an air chamber is provided between said valve and casing; and a fuel valve carried by said air valve and adapted to control the flow of fuel through said fuel supply nozzle.

12. In a carbureter of the class described, a suitable casing having a vertically arranged air passage in communication with the atmosphere at its lower end, a series of auxiliary air inlet ports in communication with the atmosphere, and an outlet passage through which combustible mixture may flow; a fuel supply nozzle located within said air passage; an annular projection located within said casing and surrounding the upper end of said air passage; an annular valve seat in threaded engagement with said projection; a vertically movable annular air valve located within said casing and the lower end of which valve lies opposite the ports aforesaid when said valve is in its lowermost position, said valve having an an-

- 5 nular portion adapted to coöperate with the valve seat at the upper end of said air passage; the inner surface of said casing having concentric portions of different diameters, and the periphery of said air valve having also concentric portions of different diameters adapted to move in contact with the concentric portions of said casing, whereby an air chamber is provided between said valve and casing; means for regulating the action of said air chamber; and a fuel supply valve carried by said air valve and adapted to control the flow of fuel through said fuel supply nozzle.

10 13. In a carbureter of the class described, a suitable casing having a vertically arranged air passage in communication with the atmosphere at its lower end, a series of auxiliary air inlet ports in communication with the atmosphere, and an outlet passage through which combustible mixture may flow; a fuel supply nozzle located within said air passage; an annular projection located within said casing and surrounding the upper end of said air passage; an annular valve seat in threaded engagement with said projection; a vertically movable annular air valve located within said casing and the lower end of which valve lies opposite the ports aforesaid when said valve is in its lowermost position, said valve having an annular portion adapted to coöperate with the valve seat at the upper end of said air passage; the inner surface of said casing having concentric portions of different diameters, and the periphery of said air valve having also concentric portions of different diameters adapted to move in contact with the concentric portions of said casing, whereby an air chamber is provided between said valve and casing; an air passage leading from the interior of said casing into said air chamber; an air passage leading from the atmosphere into said air chamber; an inwardly opening check valve located in said air passage; means for varying the area of said air passage; and a fuel supply valve carried by said air valve and adapted to control the flow of fuel through said fuel supply nozzle.

15 14. In a carbureter of the class described, a suitable casing having a vertically arranged air passage in communication with the atmosphere at its lower end, and an outlet passage through which combustible mixture may flow, and the inner surface of which casing is formed with concentric portions of different diameters; a fuel supply nozzle located within said air passage; a vertically movable annular air valve located within said casing and having an enlarged lower end adapted to move in contact with the concentric portion of the casing of the greater diameter, and a smaller upper end adapted to move in contact with the concentric portion of the casing of the lesser diameter, whereby an air chamber is provided between said valve and casing and above the enlarged lower end of said valve, said casing being provided with air inlet ports located adjacent enlarged lower end of the air valve and through which ports air may flow past said lower end and into the interior of said casing; and a fuel supply valve carried by said air valve and adapted to control the flow of fuel through said fuel supply nozzle.

20 15. In a carbureter of the class described, a suitable casing having an air inlet passage in communication with the atmosphere, auxiliary air inlet ports also in communication with the atmosphere, and an outlet passage through which combustible mixture may flow; a fuel supply nozzle located within said air passage; a vertically adjustable valve seat surrounding the upper end of said air passage; a vertically movable air valve located within said casing and having a portion adapted to coöperate with the valve seat at the upper end of said air passage; and a fuel supply valve carried by said air valve and adapted to control the flow of fuel through said fuel supply nozzle.

25 16. In a carbureter of the class described, a suitable casing having an air inlet passage in communication with the atmosphere, auxiliary air inlet ports also in communication with the atmosphere, and an outlet passage through which combustible mixture may flow; a fuel supply nozzle located within said air passage; a vertically adjustable valve seat surrounding the upper end of said air passage; a vertically movable air valve located within said casing and having a portion adapted to coöperate with the valve seat at the upper end of said air passage; and a fuel supply valve carried by said air valve and adapted to control the flow of fuel through said fuel supply nozzle.

30 17. In a carbureter of the class described, a suitable casing having an air inlet passage in communication with the atmosphere, auxiliary air inlet ports also in communication with the atmosphere, and an outlet passage through which combustible mixture may flow; a fuel supply nozzle located within said air passage; a vertically adjustable valve seat surrounding the upper end of said air passage; a vertically movable air valve located within said casing and having a portion adapted to coöperate with the valve seat at the upper end of said air passage; the inner surface of said casing having concentric portions of different diameters, and the periphery of said air valve having also concentric portions of different diameters adapted to move in contact with the concentric portions of said casing, whereby an air chamber is provided between said valve and casing; and a fuel supply valve carried by said air valve and adapted to control the flow of fuel through said fuel supply nozzle.

35 18. In a carbureter of the class described, a suitable casing having a vertically arranged air passage in communication with the atmosphere at its lower end, and an outlet passage through which combustible mixture may flow, and the inner surface of which casing is formed with concentric portions of different diameters; a fuel supply nozzle located within said air passage; a vertically adjustable valve seat surrounding the upper end of said air passage; a vertically movable air valve located within said casing and having an enlarged lower end adapted to move in contact with the concentric portion of the casing of the greater diameter, and a smaller upper end adapted to move in contact with the concentric portion of the casing of the greater diameter, and a

- smaller upper end adapted to move in contact with the concentric portion of the casing of the lesser diameter, whereby an air chamber is provided between said valve and 5 casing and above the enlarged lower end of said valve, said valve having a portion adapted to coöperate with the valve seat at the upper end of said air passage and said casing being provided with air inlet ports located adjacent the enlarged lower end of said air valve.
18. In a carbureter of the class described, a suitable casing having a vertically arranged air passage in communication with the atmosphere at its lower end, and 10 with the atmosphere at its lower end, and an outlet passage through which combustible mixture may flow, and the inner surface of which casing has concentric portions of different diameters; a fuel supply nozzle located within said air passage; and a vertically movable annular air valve located 15 within said casing and having an enlarged lower end adapted to move in contact with the concentric portion of the casing of the greater diameter, and a smaller upper end adapted to move in contact with the concentric portion of the casing of the lesser diameter, whereby an air chamber is provided between said valve and casing and above the enlarged lower end of said valve; said casing being provided with air inlet ports located 20 adjacent the enlarged lower end of the air valve and through which ports air may flow to control the flow of fuel through said fuel supply nozzle.
19. In a carbureter of the class described, a suitable casing having a vertically arranged air passage in communication with the atmosphere at its lower end, a series of auxiliary air inlet ports in communication with the atmosphere, and an outlet passage through which combustible mixture may flow; a fuel supply nozzle located within 25 said air passage; a vertically adjustable annular valve seat surrounding the upper end of said air passage; means for adjusting said valve seat; a vertically movable annular air valve located within said casing and the lower end of which valve lies opposite the ports aforesaid when said valve is in its lowermost position; said valve having an annular portion adapted to coöperate with the valve seat at the upper end of said air 30 passage; the inner surface of said casing having concentric portions of different diameters, and the periphery of said air valve having also concentric portions of different diameters adapted to move in contact with the concentric portions of said casing, whereby an air chamber is provided between said valve and casing; means for regulating the action of said air chamber; and a fuel supply valve carried by said air valve and 35 adapted to control the flow of fuel through said fuel supply nozzle.
20. In a carbureter of the class described, a suitable casing having a vertically arranged air passage in communication with the atmosphere and an outlet passage through which combustible mixture may flow, and the inner surface of which casing has concentric portions of different diameters; a fuel supply nozzle located within said air passage; a vertically movable annular air valve located within 40 said casing and having an enlarged lower end adapted to move in contact with the concentric portion of the casing of the greater diameter, and a smaller upper end adapted to move in contact with the concentric portion of the casing of the lesser diameter, whereby an air chamber is provided between said valve and casing and above the enlarged lower end of said valve; said casing being provided with air inlet ports located adjacent the enlarged lower end of the air valve and through which ports air may flow into the interior of said casing; and means for regulating the action of said air chamber.
21. In a carbureter of the class described, a suitable casing having an air inlet passage in communication with the atmosphere and an outlet passage through which combustible mixture may flow, and the inner surface of which casing has concentric portions of different diameters; a fuel supply nozzle located within said air passage; a vertically movable annular air valve located within 45 said casing and having an enlarged lower end adapted to move in contact with the concentric portion of the casing of the greater diameter, and a smaller upper end adapted to move in contact with the concentric portion of the casing of the lesser diameter, whereby an air chamber is provided between said valve and casing and above the enlarged lower end of said valve; said casing being provided with air inlet ports located adjacent the enlarged lower end of the air valve and through which ports air may flow into the interior of said casing; and means for regulating the action of said air chamber.
22. In a carbureter of the class described, a suitable casing having an air inlet passage in communication with the atmosphere, and an outlet passage through which combustible mixture may flow, and the inner surface of which casing has concentric portions of different diameters; a fuel supply nozzle located within said air passage; a vertically movable annular air valve located within 50 said casing and having an enlarged lower end adapted to move in contact with the concentric portion of the casing of the greater diameter, and a smaller upper end adapted to move in contact with the concentric portion of the casing of the lesser diameter, whereby an air chamber is provided between said valve and casing and above the enlarged lower end of said valve; said casing being provided with air inlet ports located adjacent the enlarged lower end of the air valve and through which ports air may flow into the interior of said casing; and means for regulating the action of said air chamber.

- of the casing of the lesser diameter, whereby an air chamber is provided between said valve and casing and above the enlarged lower end of said valve; said casing being provided with 5 air inlet ports located adjacent the enlarged lower end of the air valve and through which ports air may flow into the interior of said casing; an air passage leading from the atmosphere into said air chamber; and 10 means for varying the area of said last mentioned air passage.
23. In a carbureter of the class described, a suitable casing having an air inlet passage in communication with the atmosphere, and 15 an outlet passage through which combustible mixture may flow, and the inner surface of which casing has concentric portions of different diameters; a fuel supply nozzle located within said air passage; a vertically 20 movable annular air valve located within said casing and having an enlarged lower end adapted to move in contact with the concentric portion of the casing of the greater diameter, and a smaller upper end adapted 25 to move in contact with the concentric portion of the casing of the lesser diameter, whereby an air chamber is provided between said valve and casing and above the enlarged lower end of said valve; said casing 30 being provided with air inlet ports located adjacent the enlarged lower end of the air valve and through which ports air may flow into the interior of said casing; an air passage leading from the interior of said casing 35 into said air chamber; and an air passage leading from the atmosphere into said air chamber.
24. In a carbureter of the class described, a suitable casing having an air inlet passage 40 in communication with the atmosphere, and an outlet passage through which combustible mixture may flow, and the inner surface of which casing has concentric portions of different diameters; a fuel supply nozzle located within said air passage; a vertically 45 movable annular air valve located within said casing and having an enlarged lower end adapted to move in contact with the concentric portion of the casing of the greater

diameter, and a smaller upper end adapted 50 to move in contact with the concentric portion of the casing of the lesser diameter, whereby an air chamber is provided between said valve and casing and above the enlarged lower end of said valve; said casing being 55 provided with air inlet ports located adjacent the enlarged lower end of the air valve and through which ports air may flow into the interior of said casing; an air passage leading from the interior of said casing into 60 the said air chamber; an air passage leading from the atmosphere into said air chamber; and means for regulating the flow of air through said last mentioned air passage.

25. In a carbureter of the class described, 65 a suitable casing having an air inlet passage in communication with the atmosphere, and an outlet passage through which combustible mixture may flow, and the inner surface of which casing has concentric portions of different diameters; a fuel supply nozzle located within said air passage; a vertically 70 movable annular air valve located within said casing and having an enlarged lower end adapted to move in contact with the concentric portion of the casing of the greater diameter, and a smaller upper end adapted 75 to move in contact with the concentric portion of the casing of the lesser diameter, whereby an air chamber is provided between said valve and casing and above the enlarged lower end of said valve; said casing 80 being provided with air inlet ports located adjacent the enlarged lower end of the air valve and through which ports air may flow 85 into the interior of said casing; an air passage leading from the interior of said casing into said air chamber; an air passage leading from the atmosphere into said air chamber; an inwardly open check valve located within 90 said last mentioned air passage; and means for regulating the flow of air through said last mentioned air passage.

In testimony whereof, we have signed our names to this specification this 25th day of 95 February 1916.

JOHN JAY HAWTHURST, JR.
EDWARD FRANKLIN NICOLAI.
